UNITED STATES PATENT OFFICE.

EDMUND SCHULTE AND JOSEPH WEITE, JR., OF BRONXVILLE, NEW YORK; SAID SCHULTE ASSIGNOR TO SAID WEITE.

SMOKER'S UTENSIL.

1,364,892.

Specification of Letters Patent. Patented Jan. 11, 1921.

Application filed May 29, 1919. Serial No. 300,757.

To all whom it may concern:

Be it known that I, EDMUND SCHULTE, a citizen of the United States, residing at Bronxville, county of Westchester, and State 5 of New York, and I, JOSEPH WEITE, Jr., a citizen of the United States, residing at Bronxville, county of Westchester, and State of New York, have invented certain new and useful Improvements in Smokers' Utensils, 10 of which the following is a specification.

This invention relates to appliances for smokers, particularly to devices which aim to provide combinational means for the smoker's comfort and convenience.

15 One object of our invention is to provide in combination, a stand comprising an ash receptacle at the bottom thereof, cigar and cigarette holders or trays, a match or match box holder, and a cigar cutter, at the top 20 thereof.

Another object is to provide a shutter at the bottom of said stand operable from the top thereof to discharge the collected ashes therefrom.

25 These and other objects will become apparent in the description below, in which characters of reference refer to like named parts on the drawing.

Figure 1 is a longitudinal section of the 30 device taken on the plane 3—3 of Fig. 2.

Fig. 2 is a top view of the device.

Fig. 3 is a bottom view of the device.

Fig. 4 is a longitudinal section of the upper portion of the device taken on the plane 35 4—4 of Fig. 2.

Fig. 5 is a vertical section through the cigar cutter and match container.

Referring more particularly to the drawings, 1 represents a hollow standard or tube 40 having a bell-shaped base or pedestal 2 supported on feet 3. The top 4 of said standard is spread out into the form of an inverted bell. A ring band 5 sits in the top of said part 4, flush with the flange extension 6. A 45 pair of rods or beams 7 bridge said ring 5, and support thereon concentric rings 8 having serrations or the like 9 on the upper surface thereof. An elbow 10 has one end rigid to the innermost ring 8 and the other projecting downward, for a purpose which will presently be described.

In substantially the center of said beams 7 is mounted, rigid thereto, and within said rings 8, a substantially cylindrical barrel 55 or pedestal 11, open at both ends, having

fork-like upwardly projecting portions 12, adapted to hold a box of matches, or other match container, therebetween. Contained on the top of said pedestal 11 and between the portions 12, is a combined cigar cutter and match box holder 13, shown in detail in Fig. 5. Referring to the latter, 14 is a substantially rectangular hollow frame having cupped openings 15 at each end adapted to receive the end of a cigar. Slots are cut into 60 the top of the frame 14 to permit elbow levers 16 to slide therein. The lower projections 17 of said levers are equipped with bosses 18 which securely hold cutting blades 19. It is apparent that, on depression of a 65 lever 16, its blade 19 passes down over the opening 15, thus being adapted to cut off the end of a cigar. A transverse rod 20, supported within the frame 14, has coiled about it a spring 21, whose ends are prolonged to 70 engage the shoulders 22 of the bosses 18, thus retaining said blades normally elevated above the openings 15. An open-ring-like or substantially U-shaped clamp 23 is mounted on the top of said frame 14 to 75 clamp and retain a box of matches.

A wire or cord 25 having its upper end shaped as shown at 24, passes down the hollow standard into the base, where it is pivotally attached at 26 to a shutter 27 pivoted at 28. Said shutter, when closed, covers the outlet provided from the ash chamber inclosed by the walls 29. The spindle 28 is nearer the end opposite the pivot 26, so that the shutter rests normally closed by its own 80 weight. The upper loop in the end 24 of the wire 25 provides a handle for lifting the same, and the lower loop a catch which is retained by the elbow 10. It is thus apparent that when the ash chamber is to be emptied, 85 the wire 25 is simply removed by the handle 24 from the elbow 10 and lifted, thus tilting the shutter 28 and discharging the contents of the chamber. On release of the wire, the shutter is again closed.

Having thus described our invention, what we claim and desire to secure by Letters Patent, is as follows:—

1. A device of the class described comprising a hollow standard, a base therefor 105 containing an ash receptacle, a discharge shutter for said receptacle, and means located adjacent the top of the standard for operating said shutter.

2. A device of the class described compris- 110

ing a hollow standard having a flared open top of greater width than the body of said standard and a base containing an ash receptacle, a shutter for said receptacle, and 5 means for operating said shutter from the top of said standard.

3. A device of the class described comprising a hollow standard having a flared open top of greater width than the body of said 10 standard and a base containing an ash receptacle, a shutter for said receptacle, and means for operating said shutter from the top of said standard, said means passing through said standard.

15 4. A device of the class described comprising a hollow standard, a base therefor containing an ash receptacle, a discharge shutter for said receptacle, and means including a member extending up through the stand- 20 ard to the top thereof, for operating said shutter.

5. A device of the class described comprising

ing a hollow standard having a flared open top of greater width than the body of said standard and a base containing an ash tray 25 therein, a shutter for said tray pivoted near one end, a rod passing through said standard pivoted near the other end, said rod projecting through the top of said standard.

6. A device of the class described comprising a hollow standard having a flared open top of greater width than the body of said standard and a base containing an ash tray therein, a shutter for said tray pivoted near one end, a rod passing through said standard pivoted near the other end, said rod projecting through the top of said standard, and having a curved end, and a lug in the top of said standard adapted to removably retain said curved end. 35

40 In testimony whereof we have affixed our signatures.

EDMUND SCHULTE.
JOSEPH WEITE, JR.
